UNITED STATES PATENT OFFICE.

WILLIAM M. GILBERT, THEODORE M. GILBERT, AND WILLIAM C. NASH, OF NEENAH, WISCONSIN.

WIRE OR FELT GUIDE FOR PAPER-MAKING MACHINES.

SPECIFICATION forming part of Letters Patent No. 694,868, dated March 4, 1902.

Application filed September 3, 1901. Serial No. 74,061. (No model.)

To all whom it may concern:

Be it known that we, WILLIAM M. GILBERT, THEODORE M. GILBERT, and WILLIAM C. NASH, citizens of the United States, and residents of Neenah, in the county of Winnebago and State of Wisconsin, have invented certain new and useful Improvements in Wire or Felt Guides for Paper-Making Machines, of which the following is a specification.

10 Our invention relates to improvements in wire or felt guides for regulating the travel sidewise of the making-wires or felts of paper-making machines, and has for its object the avoidance of the irregular operation which 15 has heretofore been experienced in the use of said guides as usually made when applied to fast-running paper-making machines such as are now in general use; and it consists of the use of a guide arranged to be engaged by one 20 edge of the making-wire, the mechanism supporting said guiding means being provided with a spring for a slight pressure of said guide against the edge of the making-wire or felt at all times when it is running in its normal 25 line of travel and being also provided with a second spring with other coöperating devices for changing the travel sidewise of said making-wire or felt, as will hereinafter be fully described.

30 Our invention is illustrated in the accompanying drawings, in which—

Figure 1 is a side elevation of a complete wire or felt guide as it is applied to one end of the roll which supports and carries the 35 making-wire. It should be understood that the guide is adapted for the guiding of the felts as well as the making-wires, although only the latter is shown and the description will be confined to said wire. Fig. 2 is an 40 end elevation of the same and showing a part of one end of said roll and a section of the making-wire thereon. Fig. 3 is a top view of said parts as shown in Fig. 2. Fig. 4 is a detail showing a side elevation of the roll journal-box pivoted in its supporting-stand, a part 45 of the upper end of the stand being in section and showing also the ratchet-wheel in position therein. Fig. 5 is an elevation of the guide-plate supporting stand or holder, its 50 lower portion being in section upon the line *a a* of Fig. 1. Fig. 6 is a side elevation of

guide-rollers mounted for revolution upon the stem 34' of the holder 33 for use in guiding the making-wire instead of the guide-plate, as shown in Fig. 1. Fig. 7 is a plan showing 55 the top end of said rollers and a small section of the making-wire, one edge of which is in contact with the inner face of said rollers. Figs. 1, 2, 3, 4, 6, and 7 are upon the same scale and Fig. 5 upon a larger scale. 60

Similar numerals indicate like parts in the several views.

1 indicates the stand supporting the journal-box of the end of the making-wire supporting-roll, which roll is movable lengthwise 65 of said wire for changing the sidewise movement of said wire; 2, a way along the top of said stand; 3, a shelf at the rear side of said stand; 4, a sliding stand arranged to slide upon the way 2 and shelf 3; 4', a pin projecting out from the upper end of the stand 4; 5, the roll journal-box pivoted upon the pivot 5' in the stand 4; 6, the making-wire carrying-roll; 7, its journal; 8, a crank-wheel secured upon the outer end of said journal; 9, 75 a crank-pin therein; 10, a screw-shaft mounted in the sides of the stand 1 in a fixed position; 11, a ratchet-wheel screw-threaded and mounted upon the shaft 10; 12 12', depending ears of the stand 4, between which the 80 threaded hub 11' of the ratchet-wheel is closely fitted; 13, a double pawl having dogs 14 14' in its depending arms; 15, a link suspending the double pawl from the crank-pin 9; 16, a guiding-link for said pawl, connecting it by 85 means of the pin 4' with the sliding stand 4; 17, a pin connecting the upper end of the pawl 13, the links 15 and 16; 18, set-screws securing dogs 14 14' in position; 19, a pin extending out from the pawl near the dog 14; 90 20, an arm extending out from the stand 1 and being bolted to it with bolts 20'; 21 and 22, arms extending in opposite directions from the outer end of the arm 20 and parallel with the roll 6; 23, drop-hangers depending 95 from the arms 21 and 22; 24, a rod mounted for an easy oscillation in said hangers; 25 25', set collars for holding the rod from endwise movement; 26, an arm extending upward from the outer end of said rod; 27, a link connecting the arm 26 and pin 19 of the pawls; 28, a spring mounted upon the rod 24, which when 100

properly adjusted will hold the guide which engages the edge of the making-wire very lightly against said edge, one end of the spring being connected with the arm 22 and the other with the set collar 25', the latter collar being adjustable for producing the desired action in the several parts; 29, a slot arranged longitudinally of the arm 21; 30, an angular arm extending upward from the arm 21 and being adapted to be secured thereto at any desired point in its length with the hand-bolt 31; 32, a rod mounted for easy oscillation in the upper end of the arm 30; 33, a holder mounted to oscillate easily upon the rod 32, its normal position thereon being nearly vertically upward; 34 and 34', stems extending upward from the upper end of the holder 33; 35, a guide-plate secured to the stem 34, its inner face being arranged to engage the edge of the making-wire; 36, the making-wire; 37, a slot from the lower end through the holder 33 in a direction transversely of the bore for receiving the rod 32 and extending to a point a little above the center of said bore; 38, a pin extending out from said rod upon the side adjoining the making-wire and being arranged to engage the upper end of said slot 37 and limit the oscillation of the holder toward said wire beyond a nearly vertical position; 39, a spring arranged upon the rod 32 for holding the upper end of the slot 37 against the pin 38, one end of the spring being connected with the holder and the other with a set collar 40 upon the rod, whereby any desired tension may be given to said spring; 41, an arm secured upon one end of the rod 32 and extending horizontally at right angles therewith; 42, an arm secured upon the rod 24 and extending at right angles with it; 43, a link connecting the outer ends of the arms 41 and 42; 44, rolls arranged upon the stem 34' for use as a substitute for the guide-plate 35.

In adjusting the parts for running the guide-roll 6 should be set so that the making-wire will run in about its proper position. The arms 41 and 42 should be so that the outer end of one is directly over the outer end of the other, and the springs should be adjusted, being careful to get the spring 28 with only sufficient tension to throw the wire-guide up against the making-wire very lightly, so that the guide can be tilted easily. The spring 39 should be given much more tension than the spring 28.

The roll 6 revolving continuously, the action of the crank 8 and double pawl 13 will be to move the dogs 14 and 14' up and down continuously, and whenever the running to one side of the normal line of travel of the making-wire acts upon the guide and by its connections with the pawl brings the dogs upon either side of the ratchet-wheel into engagement with the teeth thereof the turning around of said wheel upon the screw 10 will move the journal-box of the roll 6 along upon the way 2, and thereby change the angle of

said roll with the making-wire until its position is corrected.

Should the making-wire be inclined to run inward or away from the guide, said guide will follow the making-wire by reason of the action of the spring 28 until the dog 14 engages the teeth upon the left-hand side of the ratchet-wheel (see Fig. 1) and by the turning of said wheel upon the screw-shaft 10 moves the journal-box 5 until the angle of the roll with the making-wire is changed and said wire assumes its proper position.

Should the making-wire run too much outward and bear too hard against the guide, the spring 39 will then come into use and allow the guide to swing outward to a greater distance than it could if said spring were not so applied. The bearing of the making-wire against the guide beyond a determined amount will swing it outward and through the action of connecting-links 27 and 43 bring the dog 14' into engagement with the teeth upon the right-hand side of the ratchet-wheel and, turning it upon the screw-shaft, will change the angle of the making-wire with the roll until said wire assumes its proper position, when neither of the dogs will engage the teeth of the ratchet-wheel.

The making-wire often runs outward to one side of its proper line of travel faster than the action of the dogs upon the teeth of the ratchet-wheel will turn said wheel and move the journal-box for correcting the running of said wire, and the spring 39 allowing the guide to swing outward permits such faster side-wise movement without any danger of so great a pressure of the edge of said wire against the face of the guide as to cause said edge to buckle and become broken.

The particular object of the slot in the holder 33 of the pin 38 and spring 39 is to permit this faster movement of the making-wire outward against the guide without the pressure of the edge of the wire against the guide that would occur if said spring were not thus arranged, and thereby permitting a plate or vertically-arranged guide to be used for guiding the making-wire.

Side plates, one on each side of the making-wire, have long been in use; but their excessive wear upon the edges of the wire has made their use objectionable; but with this improvement and the use of the guide upon but one edge of the wire, which is all that is required when the spring 39 is used, this excessive wear of the guide upon the edge of the wire, which is caused principally by the friction of the heavy bar for connecting the two guide-plates, is avoided and the use of a vertically-arranged guide made successful.

It will be obvious to practical paper-makers that the holder 33, mounted upon a rod for oscillation and being provided with the slot 37, pin 38, and spring 39, modified to suit the conditions existing relative to any particular paper-making machine, are adapted to be used with guide-plates located one on each side of

the making-wire and being connected to one another by means of a bar extending across said machine; but that plan is not advised, as it involves unnecessary expense in construction, in operation, and in wear upon the edges 5 of the making-wire.

In using the rolls 44 instead of the plate for guiding the wire there may be one or any number which seems desirable in any particular case.

Having described our invention, what we claim, and desire to secure by Letters Patent, is—

1. In a wire or felt guide for paper-making machines having a guiding-roll adapted for carrying said wire or felt and mechanism for moving one end of said roll forward or backward in a line parallel with the normal line of travel of said wire or felt by the action 15 thereon of said wire or felt against its guiding device, a guide therefor arranged to be continuously borne against by one edge of said wire or felt, said guide being mounted upon a holder which is arranged for an easy oscillation 20 upon a horizontally-arranged rod, means for limiting the oscillation upon said rod of said holder toward said wire or felt to a position slightly beyond a vertical line, and a spring arranged for holding said holder normally in said position, substantially as described. 25

2. In a wire or felt guide for a paper-making machine having a guiding-roll adapted for carrying said wire or felt and mechanism for moving one end of said roll forward or backward 30 in a line parallel with the normal line of travel of said wire or felt by the action thereon of said wire or felt against its guiding device, a guide therefor arranged to be

continually borne against by one edge of said wire or felt, said guide being mounted upon a holder which is arranged for an easy oscillation upon a horizontally-arranged rod, a slot 40 in the lower end of said holder transversely of said rod, a pin in said rod arranged to engage the upper end of said slot and limit the oscillation of said holder toward the making-wire or felt to slightly beyond a vertical position, and a spring arranged for holding the upper end of the aforesaid slot against said pin, substantially as described. 45

3. In a wire or felt guide for a paper-making machine having a guiding-roll adapted for carrying said wire or felt and mechanism for moving one end of said roll forward or backward 50 in a line parallel with the normal line of travel of said wire or felt by the action thereon of said wire or felt against its guiding device, a guide therefor arranged to be continually borne against by one edge of said wire or felt, said guide being mounted in a vertical position upon a holder for bearing against the edge of said wire or felt, said holder being arranged for an easy oscillation upon a horizontally-arranged rod, means for 55 limiting the oscillation upon said rod of said holder toward said wire or felt to a position but slightly beyond a vertical line, and a spring arranged for holding said holder normally in said position, substantially as de- 60 scribed. 65
